JACOB S. AYDELOTT, OF XENIA, INDIANA.

PARLOR BASE-BALL GAME.

SPECIFICATION forming part of Letters Patent No. 336,076, dated February 16, 1886.

Application filed November 21, 1884. Serial No. 148,498. (No model.)

To all whom it may concern:

Be it known that I, JACOB S. AYDELOTT, of Xenia, in the county of Miami and State of Indiana, have invented a new and useful 5 Improvement in Parlor Base-Ball Games, of which the following is a full, clear, and exact description.

Reference is to be had to the accompanying drawings, forming a part of this specification, 10 in which similar letters of reference indicate corresponding parts in both the figures.

The object of this invention is to provide a 15 game apparatus by means of which base-ball can be played with cards, and in which the terms used in base-ball playing will be employed with their ordinary meaning.

The invention relates to a parlor base-ball 20 game apparatus, consisting of a board or table having a base-ball ground marked thereon, and a number of cards, each bearing one or more of the technical phrases used in base-ball playing, as will be hereinafter fully described 25 and claimed.

A represents a board or table, upon which is formed a base-ball ground, B.

C represents cards, upon each of which is printed one or more of the phrases used in 30 base-ball playing, as illustrated in Fig. 2.

The cards C may be of one or more styles, and a hundred and fifty (more or less) in number.

In playing the game the cards C are shuffled, five cards are dealt to each side, and the rest of the pack is laid upon the board A, to be drawn from as may be required while playing the game. A card is drawn from the pack after each play, so that each side will always 40 have five cards from which to select a playing-card, whether the said side be at the bat or in the field. When the cards have been dealt, it is decided by consent, or in the way usually employed in base-ball playing, which side 45 shall go to the bat, the other side taking the field, beginning the play, and keeping the field until it has put out three men. Then the second side takes the bat, and keeps it until three of its men have been put out by 50 the first side. Should the field side have among its five cards one which disposes of the batter, either by "fly" or "foul out," it plays that card, which makes one out. Then the side at the bat puts another man at bat, as would be done in base-ball playing, and also 55 has the next play. If, for instance, it has the card marked "Three-base hit," it plays that and places a man on third base. Then the field side plays. Suppose, for instance, it holds the card marked "Fly out to left field" 60 and assists to home plate, two out," it plays that and retires the bat side without scoring. It is presumed in this case the man holds third base until the fly has been caught, attempts to score, and is thrown out. The 65 player must use his own judgment as to such plays, and decide them as they would be played in a real game of base-ball. Suppose, on the other hand, when the batter made a "three-base hit" the fielder could play nothing but a "strike," "ball," or "foul," then, if the batting side held "one-base hit," it plays that, and the man on the third base scores, leaving a man on first base and only one man out. The field side cannot play to 70 put out the batter again, and if the side at bat holds a card that will advance his base-runner—as one, two, three, or four base hit, "wild throw," "wild pitch," "passed ball," "fumbled grounder," "muffled fly"—or anything 75 to its own advantage, it plays that, always playing to win. If it plays "Wild throw to second by catcher, runner takes third," and the field side holds the card "Fly out to pitcher," and plays it, this makes two out and a 80 man on third. Suppose, now, the batting side cannot play to score the man on third, but plays a "foul" or a "ball," then the field side plays the card "Hit to left field and assist at home, out at home." This retires the bat- 85 ting side, three men having been put out, and the fielding side takes the bat.

In playing the game the field and batting sides play against the interest of each other every time their cards will admit of their doing so. There are times when the side in the field cannot play anything but a base-hit. This has been partly provided for by every "one-base hit" card bearing also the word "Strike" or "Ball," so that the player may 90 use the card to his best advantage, as he can play "ball" or "strike," instead of giving the batting side the benefit of the base-hit.

All cards bearing "Ball" or "Strike" can be used by the player in the manner that will benefit him most. If his side is at the bat, as a "ball" against his opponent. If his side is in the field, as a "strike," and so on. If in any 5 inning the field side plays "three strikes," the man then at the bat is out. If the side at the bat has six or seven balls in its inning at bat, the League or American rules being used, then the man at the bat takes first base, and each 10 succeeding man forced advances a base, as in the real game. This case is played in this way, because it is not probable that "three strikes" or "seven balls" can be played on any one batter, so in playing as above described "three 15 strikes" and "base on balls" are introduced, as in the real game. If at any time either side holds five cards, neither of which can be played with sense, the position of the men on the other side not permitting a sensible play, the player 20 must draw from the pack until he obtains a card that can be properly played, after which he must not draw a card after each play until his cards have been reduced to four, when he again draws in the usual manner.

25 To illustrate what is meant by a play without sense, suppose the player for the field side holds the cards "Assist from catcher to second and out," "Caught napping at first by pitcher," "Hit to second and assist to third, out at 30 third," "Hit to third and out at home," and "Thrown out at third by catcher," and the player for the batting side has no men on bases, the above-mentioned cards cannot be played with sense, as the catcher cannot make assists 35 to bases and out unless there is a man there to be put out, and so with the other cards. For this reason the player has the right to draw from the pack in such cases.

As there are but four bases, four men are all 40 that are necessary for each side to have to score the game and keep men at the proper places.

If desired, eighteen names can be selected and a record kept, the same as if a real game 45 of base-ball were being played.

The possible scores in nine innings are 0 to 0 up to 20 to 12.

If the game is a tie at the end of the ninth inning, enough extra innings may be played to give one side the lead in the score, both sides 50 having played the same number of innings.

The board, it will be seen, forms an important part of the apparatus, as in operation the player-cards are placed thereon at the proper points, according as they make a one, two, or 55 three base hit, and are transferred from time to time as they advance toward the home-base or are removed as put out from the board. Thus I have a visible representation of the progress of the game, so that the board will at 60 all times show the position of those of the batting-nine who are in the field.

Having thus fully described my invention, I claim as new and desire to secure by Letters Patent—

1. A parlor base-ball game apparatus consisting of a board or table provided with the representation of a base-ball ground, and a number of cards comprising a plurality of series, one of which represents the several 70 plays of which the batter is capable, and another the technical phrases representing the disposition that may be made of the batter, substantially as set forth.

2. A base-ball game apparatus comprising a 75 game-board having marked thereon the representation of a base-ball field, such representation operating to denote the positions of the various players, a number of cards having words or characters whereby to represent the 80 several plays which may be made, and a number of sets of cards which decide the fate of the players, said cards, when placed at proper points on the board, also operating to represent the players, substantially as set forth.
